ATTORNEY

UNITED STATES PATENT OFFICE.

MATTHEW O. BECKNER, OF ROANOKE, VIRGINIA.

FLY-CATCHER.

1,280,371.

Specification of Letters Patent.

Patented Oct. 1, 1918.

Application filed June 9, 1917. Serial No. 173,810.

To all whom it may concern:

Be it known that I, MATTHEW O. BECKNER, a citizen of the United States, residing at Roanoke, in the county of Roanoke and 5 State of Virginia, have invented certain new and useful Improvements in Fly-Catchers, of which the following is a specification.

This invention has relation to fly catchers, and has for an object to provide a device of 10 this character embodying a suction fan to draw the flies into a receptacle provided to receive the same.

Another object of the invention is to provide a fly catching device of this nature 15 adapted to be located upon the front end of a motor car, and to be operated by the engine thereof whereby flies may be collected during forward travel of the car.

Another object of the invention is to provide 20 a fly catching device of the character above noted adapted to be carried about in the hand for use in confined spaces.

In addition to the foregoing my invention comprehends improvements in the details of 25 construction and arrangement of the parts to be hereinafter more fully described and particularly set forth in the appended claim.

In the accompanying drawings in which 30 similar and corresponding parts are designated by the same characters of reference throughout the several views in which they appear:

Figure 1, is a view in front elevation of a 35 motor vehicle illustrating the application thereto of my invention.

Fig. 2, is a view in longitudinal section of my invention illustrating the method of operatively connecting the same with the motor 40 and.

Fig. 3, is a view in side elevation of a portable form of my improved fly catcher.

With reference to the drawings 10 indicates the hood of a motor vehicle, and 11 the 45 radiator provided with the usual filling cap 12 located centrally of the car and at the top of the radiator. The cooling fan 13 of the motor is provided for the purposes of my invention with a forward extension of its 50 shaft indicated at 14. The headlights 15 in accordance with the usual custom are mounted upon U-shaped brackets 16 at either side of the machine.

My improved fly catcher comprises a funnel-shaped member 17 which is located in 55 front of the radiator with its small end

directed rearwardly. The small end of the funnel shaped member is directed downwardly to form a conduit 18 which opens into a cage 19, formed preferably of foraminous material, and which is supported partly upon the front axle by means of U-bolts 20, and partly by means of a bracket 21 which supports the rear end of the cage from the chassis frame. The rear end of the cage is 60 open and provided with a hingedly mounted closure 22, normally held in closed position by means of a latch 23. The end of the conduit 18 which opens into the cage is normally closed by means of a hingedly mounted flap valve 24, held in place by means of a light spring 25, the valve being designed to 65 open into the cage.

A shaft 25 is extended through an opening 26 into the funnel shaped member, and the 70 rear end of the shaft is connected to the fan shaft 14 by means of a coupling 27. The opposite end of the shaft extends into the funnel shaped member to a point adjacent the large opening thereof and is provided with a fan 75 28. The large end of the funnel shaped member is closed with a section of wide mesh material 29 to prevent the entrance of paper or the like into the funnel.

The funnel shaped member is supported 80 by means of a brace rod 30 which is connected at one end to the periphery of the large end of said funnel member, at the highest point thereof, and extends rearwardly and is provided upon said rear end 85 with a bifurcated terminal 31 designed to embrace the filling cap 12 of the radiator. The terminals of the bifurcated portion are furthermore enlarged and apertured to permit the entrance of a bolt 32 thereinto as 90 indicated whereby to securely connect the brace rod to the filling cap. A second pair of brace rods 33 are provided, one being located at each side of the funnel shaped member, with the forward ends of the rods 95 riveted or otherwise secured thereto, and the rods extended rearwardly with their rear ends provided with sleeves 34 designed to receive one of the terminals of the U-shaped lamp brackets 16 as indicated. 100

It will be apparent that during forward travel of the vehicle, and while the fan shaft 14 is in motion, the fan 28 within the funnel shaped member will create a draft therethrough whereby to draw flies into the 110 funnel member, conveying them through the conduit 18 into the cage 19, the valve

24 being held in open position by the current of air. The cage is designed to be detached and replaced after being emptied of its contents.

5 In Fig. 3 of the drawings I have illustrated a modified form of my invention which includes a funnel shaped member 17 with a fan shaft 25 penetrating the same and provided with a suction fan, the shaft 10 however, in this instance being connected to the shaft of a motor 35 which is mounted upon a handle 36. The operation of this 15 form of my invention is the same as the form first described, in the second instance however, the device is intended to be carried in the hand and directed toward places where flies accumulate. The form associated with the motor vehicle is particularly efficacious when gathering flies in the streets 20 of a city, and particularly in the vicinity of street markets where food is exposed.

While I have illustrated and described my invention with some degree of particularity, I realize that in practice various 25 alterations thereof may be made, and I therefore desire to reserve the right and privilege of changing the form of the details of construction, or otherwise altering the arrangement of the correlated parts 30 without departing from the spirit of the invention or the scope of the appended claim.

Having thus described my invention, what

I claim as new and desire to secure by Letters Patent is:—

In a motor vehicle including the radiator 35 filler cap, the cooling fan shaft, and the front axle, the combination therewith of a funnel-shaped casing mounted forwardly of the vehicle, and having its smaller end directed rearwardly, a tubular extension 40 formed on the rear end of the said funnel shaped member extended downwardly, a spring held valve normally closing the lower end of said tubular extension, a rectangular cage of foraminous material mounted upon 45 the axle, a closure for the rear end of the cage, said cage having an opening in its forward end through which the tubular extension projects, a shaft mounted in the funnel-shaped casing for rotation, a fan 50 carried by the forward end of said shaft, means for coupling the rear end of said shaft to the cooling fan, a supporting rod secured at one end to the larger end of the funnel-shaped member, and a split band on 55 the rear end of said supporting rod to encircle the radiator filling cap to afford a support for the funnel shaped member.

In testimony whereof I affix my signature in presence of two witnesses.

MATTHEW O. BECKNER.
